UNITED STATES PATENT OFFICE.

ALFONSO CLAUDE FRENCH, OF DAINGERFIELD, TEXAS.

PLOW AND SWEEP HOLDER.

No. 911,586.

Specification of Letters Patent.

Patented Feb. 9, 1909.

Application filed August 31, 1908. Serial No. 451,020.

To all whom it may concern:

Be it known that I, ALFONSO CLAUDE FRENCH, a citizen of the United States, residing at Daingerfield, in the county of 5 Morris and State of Texas, have invented a new and useful Plow and Sweep Holder, of which the following is a specification.

This invention has relation to a plow and sweep holder and it consists in the novel 10 construction and arrangement of its parts, as hereinafter shown and described.

The object of the invention is to provide a simple and effective means for securely holding a sweep in proper position at the 15 lower end of a plow standard, and, at the same time, to provide means for holding the plow-point in a similar position.

The holder consists primarily of binary plates or members which are substantially 20 wedge-shaped longitudinally, and which are provided upon their adjacent faces with ribs and intervening furrows which are adapted to intermesh with each other, whereby the 25 said plates are held against relative rotary movement with relation to each other. One of the said plates is provided upon its forward face with lugs which are adapted to engage the inner sides of the lower portion of the plow standard and which hold the 30 said plate against edgewise movement. The other plate is provided with a lug which is adapted to lie over the upper edge of the sweep, and both of the plates are provided with elongated perforations which are 35 adapted to receive the heel bolt which also passes through the standard and the plow-point. By reason of the fact that the said members are wedge-shaped as indicated, a 40 variety of adjustments may be attained, whereby the sweep may be pitched at a desired angle with relation to the standard, and also when the sweep is not used the parts may be assembled whereby they, in connection with the heel bolt, may effect- 45 ually hold the plow-point, and this may be done irrespective of the configuration of the lower portion of the standard.

Figure 1 is an edge elevation of the holder applied. Fig. 2 is a sectional view of the 50 same. Fig. 3 is an edge elevation of the holder, showing the parts reversed. Fig. 4 is a similar view of the holder showing the parts adjusted longitudinally. Fig. 5 is a side elevation of the upper portion of one 55 plate of the holder.

The holder consists of the plates or mem-

bers 1 and 2, both of which are substantially wedge-shaped in cross section longitudinally, and which are provided upon their inner surfaces with the ribs 3 and 4 respectively and 60 the intervening furrows. The plate 1 is provided with an elongated slot 5, and the plate 2 is provided with an elongated slot 6. The plate 1 is provided upon its forward face with the lugs 7, 7, which are located at the 65 opposite ends of the said plate, and the plate 2 is provided upon its rear face with a lug 8. The plate 1 is adapted to bear against the rear edges of the standard 9 and the lugs 7 are adapted to project between the 70 side portions of the said standard, and thus afford means for preventing the said plate 1 from turning or twisting in its position upon the said standard. The heel bolt 10 passes transversely through the plow- 75 point 11, and through the lower portion of the standard 9, and also through the slots 5 and 6 of the plates 1 and 2 respectively. The nut 12 is screw-threaded upon the rear end portion of the bolt 10 and is adapted to 80 bear against the rear side of the plate 2. The intermediate portion of the sweep 13 bears against the rear side of the plate 2, and the upper edge of the said sweep is located under the lug 8 mounted upon the rear por- 85 tion of the said plate 2. Thus, it will be seen that when the parts are assembled, as described, the sweep will be positively held in proper position with relation to the lower portion of the standard and the plow-point, 90 and that the parts will be compactly held together and braced against any lateral strain or tendency to twist relative to each other. It will also be seen that by shifting the plates 1 and 2 longitudinally, the transverse thick- 95 ness of the material of which the said plates are composed may be increased or diminished, as desired, by bringing the thicker ends of said plates or members toward each other, or by moving the said thicker ends 100 away from each other. It will also be seen that the plate 1 may be reversed in its position upon the lower portion of the standard 9, and the thicker end portion of the said plate 1 may be upwardly disposed or down- 105 wardly disposed, as desired. Thus, means is provided for varying the angle at which the sweep will be presented to the ground. Also when the sweep 13 is dispensed with the nut 12 may be screwed up against the rear 110 surface of the plate 2 and said plate may be adjusted longitudinally as above described.

Thus means is provided for holding the plow-point in position, and, should the configuration of the lower portion of the standard be such as to throw the rear surface of the plate 5 2 out of parallel relation with the forward upper portion of the point 1 when the plates are in one position the plate 1 may be reversed in its position, whereby the rear surface of the said plate 2 may be brought into 10 parallel relation with the upper portion of the plow-point. Thus, the nut 12 may be caused to fit squarely against the rear surface of the said plate 2.

Having described my invention, what I 15 claim as new, and desire to secure, by Letters Patent, is:—

The combination with a plow standard, a sweep and a heel-bolt, of a sweep-holder secured to the standard by the heel-bolt, and composed of two adjustable wedge-shaped members, one of which is provided with means for engaging the plow standard, and the other with means for engaging the sweep, both of said members having elongated slots 20 for the reception of the heel-bolt.

In testimony that I claim the foregoing as my own, I have hereto affixed my signature in the presence of two witnesses.

ALFONSO CLAUDE FRENCH.
